MUFFLER

Winthrop T. Scarritt, Utica, N. Y.

Application February 21, 1934, Serial No. 712,362

2 Claims. (Cl. 137—160)

This invention relates to certain improvements in mufflers or silencers particularly designed for use in connection with the exhaust of internal combustion motors in order to effectively deaden the sound waves resulting from the explosions without the setting up of detrimental back pressure.

The invention provides an improved muffler or silencer of the indicated character embodying means which is so constructed and arranged as to deflect and break up the sound waves into a plurality of whorls or eddy streams which interact to nullify the explosive peaks of the sound waves.

The invention more particularly resides in a muffler or silencer which is so constructed as to provide a main passage and a sound deadening chamber with ports establishing communication therebetween, which ports are so constructed and located as to cause the deflection and breaking up of the sound waves into a plurality of streams which pass through the ports and form interacting whorls or eddies in the deadening chamber which function to deaden the explosive peaks of the sound waves.

The invention further contemplates a muffler or silencer in which the gases and sound waves traveling at high velocity through a restricted passage are directed in the form of streams or whorls through ports into an enlarged deadening chamber where the streams or whorls expand and interact upon each other to effectively deaden the sound waves.

The invention further comprehends a muffler or silencer provided with inner and outer tubular casings defining a passage for the gases and sound waves, and an expansion and deadening chamber, and with means in the inner casing extending into the passage for deflecting and causing the gases and sound waves to pass from said passage into the chamber in a plurality of whorls or streams.

The invention further provides a muffler which is relatively simple in construction, is light in weight and may be produced at low cost and which is efficient for its intended purpose without the setting up of detrimental back pressure.

With the above recited and other objects in view, reference is made to the following specification and accompanying drawing in which there is set forth two forms of the invention.

In the drawing:

Fig. 1 is a longitudinal vertical sectional view of a muffler embodying the invention.

Fig. 2 is a cross sectional view taken approximately on the line 2—2 of Fig. 1.

Fig. 3 is a longitudinal vertical sectional view of a modified form of the invention.

Fig. 4 is a cross sectional view taken approximately on the line 4—4 of Fig. 3.

Referring to the drawing by characters of reference, the muffler or silencer illustrated in Figs. 1 and 2 thereof, include an elongated tubular casing or shell 10 and end heads 11 and 12 connected to the open ends of the shell 10 in any desired manner, and provided with outwardly projecting tubular bosses or collars 13 for respectively connecting the muffler to the exhaust and tail pipes and providing an inlet and outlet for the muffler. The shell 10 may be of any desired cross sectional configuration and may be of sheet metal or cast or otherwise formed. In the instant embodiment, the shell 10 is shown as of circular cross sectional formation and the end heads 11 and 12 are provided with marginal flanges 14 which are welded or otherwise secured within the opposite ends of the casing 10.

The casing 10 is subdivided into longitudinally extending compartments A and B by means of a longitudinally disposed tubular shell 15 which is located intermediate the ends of the casing 10, preferably concentric therewith, and which is supported by the casing 10 in any desired manner. As illustrated in Figs. 1 and 2, the shell 15 is connected to the casing 10 by frusto-conical frames 16 and 17 having their larger ends disposed towards the muffler inlet and formed with outer marginal flanges 18 welded or otherwise secured to the inner periphery of the casing 10. The foremost frame 16 is provided at its inner edge with a rearwardly directed tubular boss 19 fitted over the forward end of the shell 15 and welded or otherwise secured thereto, while the rearmost frame 17 is also formed with a rearwardly directed tubular boss 20 at its inner edge which snugly fits the rear end of the shell 15 but which is unsecured thereto in order to permit of relative sliding movement of the shell 15 with respect thereto so as to compensate for contraction and expansion.

In the embodiment of the invention illustrated, the compartment A constitutes a main passage for the gases and the sound waves, while the compartment B functions primarily as a sound wave expansion and deadening chamber. The shell 15 is provided with a plurality of longitudinally spaced sets of inwardly directed louvers 21, the louvers in each set being spaced circumferentially of the shell and alternate sets, if desired, being disposed in staggered relation, as shown. The louvers 21 are so fashioned as

to provide scoop-shaped projections having forwardly disposed inlet ends or ports 22 which intercept the gases and sound waves as they pass through the compartment or passage A and direct the same into the expansion and deadening chamber B in the form of streams or whorls, which streams or whorls expand and interact to nullify the explosive peaks of the sound waves. The louvers 21 may be of any desired form, but as illustrated, the same are produced by slitting the shell 15 circumferentially and pressing inwardly the portions of the shell lying in the rear of each slit into the form of scoop-like projections.

15 The frames 16 and 17 are each provided with annularly spaced rearwardly directed louvers 23 similar in construction to the louvers 21 and which project radially inwardly so that the gases and sound waves passing through their outlet ends or ports 24 are directed inwardly in order to interact with and diffuse the sound waves emitted respectively through the louvers 21 and through the rear of the shell 15.

Forwardly of the shell 15 and rearwardly thereof, the casing 10 may be provided with one or more baffles 25, one being shown in the instant embodiment, forwardly of the shell and one rearwardly thereof, which are similar in construction to the frusto-conical frame 16 and which have their outer marginal flanges 26 welded or otherwise secured to the inner periphery of the casing 10. The baffles 25 thus subdivide the casing forwardly of the shell 15 and rearwardly thereof, into longitudinally spaced compartments or expansion chambers each with a restricted passage 27 formed by the tubular boss 28 establishing communication therebetween.

In the form of the invention illustrated in Figs. 3 and 4 of the drawing, a tubular shell 29 extends longitudinally of the casing 30 between the end heads 31 and 32, and has its forward end welded or otherwise secured in the tubular boss or collar 33 of the end head 31, while its rear end snugly fits the tubular boss or collar 34 of the end head 32, but which is unsecured therein to admit of relative sliding movement so as to compensate for contraction or expansion of the parts. The shell 29 thus subdivides the casing into longitudinally extending compartments C and D, the compartment C constituting a main passage for the gases and sound waves, while the compartment D functions as a sound wave expansion and deadening chamber.

The shell 29 is provided with a plurality of longitudinally spaced sets of inwardly directed louvers 35 which may be of any desired form, but which, as illustrated, are similar in construction to the louvers 21 and, if desired, are arranged with alternate sets in staggered relation. The louvers 35 function to intercept the gases and sound waves passing through the main passage C and to deflect the same into the expansion and deadening chamber D in the form of streams or whorls which interact to nullify or blanket the peaks of the sound waves.

What is claimed is:

1. A silencer of the character described including an elongated casing, a shell within said casing and a frame adjacent each end of said shell securing the same in spaced relation within the casing to provide a chamber between the shell and casing, said frame having rearwardly and inwardly flared conical walls with annularly spaced apertured portions opening into and out of said chamber respectively, and rearwardly directed inwardly inclined radial louvers projecting from the edges of the apertured portions to overlie the apertures respectively, and said shell having a plurality of longitudinally spaced sets of inwardly struck forwardly projecting louvers defining ports and sound wave deflecting means for intercepting and deflecting the sound waves within said shell to form a plurality of streams as they pass through said ports into said chamber.

2. A silencer of the character described including an elongated casing, a shell within said casing and a frame adjacent each end of said shell securing the same in spaced relation within the casing to provide a chamber between the shell and casing, said frame having rearwardly and inwardly flared conical walls with annularly spaced apertured portions opening into and out of said chamber respectively, and rearwardly directed inwardly inclined radial louvers projecting from the edges of the apertured portions to overlie the apertures respectively and said shell having a plurality of longitudinally spaced sets of semi-elliptical apertures opening into the said chamber and inwardly struck forwardly projecting louvers of longitudinal and transverse concavo-convex form secured about the curved edges of the aperture portions respectively to define ports and sound wave deflecting means for intercepting and deflecting the sound waves within said shell to form a plurality of streams as they pass through said ports into said chamber.
